AIR DRIVEN VIBRATOR

John D. McKellar, Inglewood, Calif.

Application September 9, 1955, Serial No. 533,271

2 Claims. (Cl. 259—1)

This invention relates to mechanical vibrators, and more particularly, to a vibrator of the type utilizing one or more rotating eccentric weights to produce a shaking force.

Vibrators or shakers are used in many industrial and constructional operations for various purposes, such as on test fixtures for determining the ability of components to withstand vibration, to agitate feed hoppers or various types of cutting blades, and to mix, settle, or level thick fluid compositions. The present invention is especially suitable for shaking concrete forms, such as when pouring concrete pipe sections.

Presently known and used devices of this nature consist of an eccentric weight, or two geared eccentric weights, driven by an entirely separate electric or air motor connected thereto. The mounting shafts or other mounting means are journaled in a housing which is adapted to be rigidly attached to the concrete form or whatever device is to be vibrated. These assemblies are thus rather complicated and expensive, having relatively many actual operating elements.

It is a general object of the present invention to provide a vibrator for the above described purposes which is extremely simple, rugged, and inexpensive.

Another object of this invention is to provide such a vibrator having substantially fewer moving or operating parts than are necessary in conventional vibrators.

A further object is to provide a vibrator assembly wherein the parts themselves can be made with an absolute minimum of close fitting or critical-tolerance dimensions.

Still another object of the present invention is to provide a vibrator having the above desirable features with a maximum efficiency of operation comparable to the best presently known and more complicated vibrator units.

Other objects and features of advantage will be apparent upon reading the detailed description of a preferred embodiment of this invention to follow.

Briefly, my invention comprises a basic vibrator wheel having an integral eccentric weight, integral turbine blades for being rotatably driven by air, for example, and integral gear teeth if desired. The blades are curved in one direction or plane, only, and are essentially straight in the length dimension thereof, which is the thickness dimension of the wheel. The wheel has these various integral elements provided thereon in such a manner and in such locations that the wheel as thus defined comprises a single castable component requiring only the most elementary molding and casting procedures to manufacture, as will be referred to in more detail later. The vibrator wheels are adaptable to being used singly, paired, or stacked in tandem as desired. A nozzle in the housing permits air under pressure to blast onto the turbine blades for rotating power, which air is then exhausted to the atmosphere.

2

In the accompanying drawings:

Figure 1 is a plan view of the vibrator with the housing cover removed.

Figure 2 is an edge interior view of the complete vibrator, partly in section, taken as indicated by the line A—A in Figure 1.

Referring to the drawings, a box or housing 1 contains two geared wheels 2 which are mounted on parallel shafts installed in the housing 1. The two wheels are of equal diameter and will rotate in opposite respective directions due to the meshing of the gear teeth on their periphery. Each wheel 2 carries an eccentric weight 3 integral therewith, this weight being large enough to provide a substantial vibrating force when the wheel is spinning.

One wheel shown herein has a plurality of turbine blades 4 located thereon as near to the toothed rim as practical. These blades 4 are also integral with the wheel, are curved in cross section, and extend on one

side of the wheel perpendicular to the plane thereof. They are further positioned so that the centers of the concave cupped surfaces are approximately tangent to radii of the wheel. In other words, they are placed at an angle which will cause the most efficient wheel driving

reaction when a jet of air is delivered through a nozzle 5 fixed in the side of the housing 1 and pointing toward the blades 4 at the wheel position where the gear teeth are in engagement with the other wheel. Both wheels could carry turbine blades if desired, in which case the

nozzle 5 would be positioned on the perpendicular bisector of a line joining the two wheel shafts. Of course, when just one wheel has blades 4, the nozzle 5 can obviously be placed at any suitable location and position in the housing, and two or more nozzles could be employed as desired.

The wheels 2 as disclosed herein represent a construction or structure entirely new and novel in the shaker art. Wheels 2 are cast (or forged) from iron, steel, or brass, or other preferred material, as a single unit containing the eccentric weight and turbine blades (and gear teeth if desired) in the wheel as formed. As shown, one

side of the wheel is completely flat and plain, in the plane of the wheel's rotation, with the eccentric weight 3 and blades 4 projecting in a "thickness" direction from

the other side, so that all draft angles are made toward this one side in a very simple manner, and no cores or loose removable pieces whatever are required in the mold or die. Of course, other wheel, weight, and blade designs could be provided in accordance with this invention,

and the present configuration is shown only by way of illustration and not limitation.

For instance, the gear teeth could be machined entirely from a circular cast wheel, since they will usually require some rough machine finishing, along with the

machining of the central hole or hub for a bushing or bearing (not shown). But this latter hole is the one and only part of the whole assembly requiring a somewhat close tolerance size. The gear teeth may be made smaller than illustrated herein, but even they need no

precision or close-tolerance fit as do gear teeth on other types of similar machinery, since they are used in this instance only for synchronizing the eccentric weights 3. No definite close clearances between running and stationary parts are necessary.

To continue with the assembly description of the present embodiment shown in Figures 1 and 2, it is noted that the eccentric weights are located directly opposite each other in the position illustrated. When the wheels 2 have rotated one-half revolution, the weights

70 will be adjacent to each other on the inside rims of the wheels. Therefore, it is seen that with this two-wheel

arrangement, a sine-wave shaking force will be produced, the resultant force acting only forward and backward in a straight line in the direction of the nozzle axis, or horizontally from right to left and left to right in Figure 1.

This illustrates a preferred and well-known arrangement of a pair of eccentric weighted wheels for a linear vibration, but it is to be distinctly understood that one eccentric weighted wheel could be used by itself, for example, to produce a rotating vector vibration for shaking concrete forms or other devices in this latter manner. Alternatively, two such wheels can be assembled on a common shaft to provide variable eccentricity by relatively fixing the eccentric weights in various positions.

The housing 1 is held together by corner bolts passing through spacers 6 and a top cover 7 (Figure 2). The wheel shafts can also comprise bolts utilizing spacers at the same relative position. The spacers 6 leave an opening all around the housing 1 for exhausting the air from nozzle 5 to the atmosphere after it has been used to spin the wheels 2.

It is thus seen that when an air line, for example, is attached to nozzle 5 and the entire housing fastened rigidly to the device to be vibrated, a simple, efficient, and rugged shaker is thereby provided, which requires no separate motor to drive it. The inexpensive parts can be quickly and easily made and assembled, and there are no adjustments to be made after initially mating the geared wheels in the desired relation. Speeds of several thousand R. P. M. (8,000 to 20,000) are preferred and easily obtainable with this invention.

My invention has met with great favor in actual commercial use. Besides its economy of manufacture, another obvious reason for its usefulness is its efficient operation. By using actual turbine blades or "buckets" in this particular new arrangement, an impulse turbine is provided wherein the air stream is reversed by the blades and the velocity pressure is effectively transferred into the desired work output, as with the well-known Pelton wheel construction. Thus, static pressure alone is not depended upon for the working force. As mentioned previously, the blades 4 are of the cylindrical

type or form, i. e., having straight elements in a direction perpendicular to the wheel face, for casting reasons.

What is claimed is:

1. A vibrator comprising a housing, a wheel rotatable on a fixed axis therein, said wheel having an eccentric weighting portion integral therewith and of the same material as said wheel, concave turbine blades normal to one face of said wheel and arranged in a ring near the periphery of said wheel, said blades also being integral with and of the same material as said wheel, all thickness elements of said wheel, including said weighting portion and said blades, being substantially straight but having a slight draft taper in a common direction, a nozzle extending through said housing and directed at the concave sides of said blades, and a cover removably secured to said housing, said cover being spaced from said housing along at least one edge thereof by spacing means at the points of cover attachment, for fluid exit, said housing being otherwise closed.
2. A vibrator comprising a housing, a wheel rotatable on a fixed axis therein, said wheel having an eccentric weighting portion thereon, concave turbine blades normal to one face of said wheel and arranged in a ring near the periphery of said wheel, a nozzle extending through said housing and directed at the concave sides of said blades, and a cover removably secured to said housing, said cover being spaced from said housing along at least one edge thereof by spacing means at the points of cover attachment, for fluid exit, said housing being otherwise closed.
